UNITED STATES PATENT OFFICE

2,621,986

JOURNAL BOX LID

Howard J. Stewart, Apollo, Pa., assignor to Union Spring and Manufacturing Co., New Kensington, Pa., a corporation of Pennsylvania

Application November 15, 1950, Serial No. 195,829

10 Claims. (Cl. 308—47)

1

This invention relates to journal box lids and, more particularly, to an improved arrangement of operating mechanism for yieldingly maintaining a lid in a position closing the opening in a journal box.

This application is a continuation-in-part application of my copending application Serial No. 35,212, filed June 25, 1948.

Journal boxes for railroad car axles, constructed in accordance with specifications provided by the Association of American Railroads, are provided with substantially square openings having pivot lugs at the upper edges thereof to which lids for closing the openings may be pivoted. It is necessary that the closure lid be yieldingly maintained in a closed position, in order that access may be had to the journal box for inspection and the replenishment of lubricant. The mechanism for this purpose has heretofore usually comprised either a lever and a coil spring, or a spring lever, together with additional operating parts having an arrangement which was of necessity complicated and apt to get out of order. In addition, a further requirement of such structures is that the lid be universally mounted for limited movement relative to the journal box so that it may automatically adjust its position to compensate for irregularities in the material defining the opening in the journal box.

One of the principal objects of this invention is to provide a journal box lid with an improved arrangement of operating parts for moving the lid to a closed position, and in which provision is made in a novel manner for universal movement of the lid on the journal box. To this end, there is provided an operating member in the nature of a housing which is pivoted to the journal box for movement independently of the closure lid. The resilient bias for yieldingly maintaining the lid in its closed position is applied through the operating member which has engagement with the lid at a single point centrally located and of substantially small area about which the lid may have universal movement to adjust its position on the journal box. The bias is applied to the operating members by means of a spring having a novel configuration and application. The biasing spring has bearing engagement with the operating member and a pivot lug on the journal box in such manner that it is the only member required to control the operation of the lid, thereby eliminating the plurality of operating parts heretofore considered essential.

Other objects and advantages of the invention will become apparent during the following description.

2

In the drawings there is shown a preferred embodiment of the invention. In this showing:

Fig. 1 is a plan view of a journal box lid and operating mechanism therefor constructed in accordance with the principles of the invention;

Fig. 2 is a sectional view of the lid taken substantially along the line II—II of Fig. 1;

Fig. 3 is a sectional view of the operating member or housing taken substantially along the line III—III of Fig. 1;

Fig. 4 is a side elevational view of the closure lid and operating mechanism mounted on a journal box, a part of the operating mechanism being broken away and the journal box being shown in section;

Fig. 5 is a side elevational view of the housing or operating member shown in Figs. 1 and 4;

Fig. 6 is a plan view of the spring employed to bias the lid to its closed position;

Fig. 7 is a side elevational view of the spring shown in Fig. 6;

Fig. 8 is a plan view of a modified journal box lid and operating mechanism having improvements which among others eliminates the necessity of hinging the lid to the journal box pin;

Fig. 9 is a side elevation of the structure shown in Fig. 8;

Fig. 10 is a sectional view taken substantially along the line X—X of Fig. 8;

Fig. 11 is an end elevational view of the modified strap employed to secure the hood to the lid in the structure shown in Figs. 8 and 12;

Fig. 12 is a plan view of a modified structure similar to that shown in Fig. 8, but in which the hood is formed by casting rather than by stamping as in Fig. 10;

Fig. 13 is a side elevation of the structure shown in Fig. 12; and

Fig. 14 is a sectional view taken substantially along the line XIV—XIV of Fig. 1.

The broken lines of Fig. 1 indicate a flange 2 on a journal box which defines a substantially square opening 3 providing access to the interior of a journal box for inspection and the replenishment of lubrication. A lid 4 is provided for closing the opening 3. The lid 4 is a sheet metal stamping or ferrous casting which is provided with a flat surface 5 on its under side for sealing engagement with the journal box flange 2. The upper edge of the stamping from which the lid 4 is formed is provided with a pair of projecting strips or tongues 6 which are doubled back to provide an opening 7 for the reception of a pivot pin 8. The opening 7, as best shown in Fig. 4, is considerably larger than the diameter of the pivot pin 8 so that the lid 4 which is pivotal about

the pin 8 may adjust its position on the journal box in a manner to be described. The pin 8 is supported by a pivot lug 9 of conventional construction, as specified by the Association of American Railroads, and constituting part of the journal box. The tongues 6 provide a hinge for the lid 4 on the pin 8. This hinge is reinforced and secured rigidly with respect to the lid 4 by a rod 10 having welded connections with a hinge 6 and lid 4 as best shown in Figs. 1 and 4.

To control the operation of the lid 4, there is provided an operating member indicated as a whole by the numeral 11. The operating member 11 is a pressed steel or cast metal housing comprising spaced side walls 12 and 13 connected together in spaced relation by a top or cover member 14. The upper portions of the side walls 12 and 13 are provided with ears 15 respectively having openings 16 for the reception of the pivot pin 8 and by which the member 11 is mounted pivotally on the pin 8. From the foregoing it will be noted that both the lid 4 and the operating member 11 are pivotal on the pin 8 independently of each other. The lower end wall 17 of the housing member 11 terminates in a flange or lip 18. The lip 18 has a substantially semi-cylindrical shape and is formed about an axis extending parallel to the axis of the opening 16 for a purpose to be described.

As best shown in Fig. 2 the central portion 19 of the lid is upset to provide a point 20. The operating member 11 is positioned on the lid 4 so that the under surface 21 of the lip 18 has contact with the point 20. By reason of the formation of the lid portion 19 to provide the point 20, the lid 4 will have limited movement about a vertical axis extending through the point 20 so that it may adjust its position to compensate for irregularities in the surface of the flange 2. The operating member 11 is secured to the lid 4 by means of a strap 22, which has its ends connected by rivets 23 to the lid 4. Instead of using rivets 23, the ends of the strap 22 may be secured to the lid 4 by welding. The center portion 24 of the strap 22 has a substantially semi-cylindrical shape and is received in nesting engagement with the inner surface of the lip 18, as best shown in Fig. 4. From Fig. 4, it will also be noted that the central portion 19 of the lid carrying the upset part or point 20 is substantially semi-cylindrical to accommodate itself for the contour of the lip 18. By reason of the semi-cylindrical contour of the lip 18 and central portion of the strap 24, the lid 4 may rock about a horizontal axis in the plane of the lid 4 and passing through the point 20. It will thus be seen that the lid 4 may rock about horizontal and vertical axes which intersect centrally of the lid 4. In this manner limited universal movement of the lid 4 is had relative to the operating member 11, and the lid 4 may readily adjust its position to compensate for irregularities in the surface of the flange 2 and thereby having sealing engagement with such flange.

For the purpose of yieldingly maintaining the lid 4 in a closed position on the flange 2 there is provided a spring 25. As best shown in Figs. 6 and 7, the spring 25 comprises two coil portions 26 and 27 formed about a common axis and respectively having free ends 28 and 29 at the adjacent ends of the coils. The remote ends 28a and 29a of the coils 26 and 27 are connected together to provide a bight 30 having a

straight portion of wire between the bight on which is mounted a roller 31. The spring 25 is formed from spring rod steel stock initially in the shape of a hairpin in which the parts 28a and 29a form the arms and are connected by the bight 30. The ends of the arms 28a and 29a are then coiled to provide the coils 26 and 27 and the free ends 28 and 29 which project upwardly toward the bight 30. The coils 26 and 27 are mounted on a cylindrical tube 32 with their free ends 28 and 29 engaged with the under surface of the cover member 14, as at 33. As best shown in Fig. 3, the side walls 12 and 13 are upset to provide inwardly extending parts 34 which project into the ends of the tube 32 and thus function to securely fasten the tube in position with respect to the operating member 11.

When there is no tension on the spring 25 the bight 30 and ends 28 and 29 will occupy the relative positions shown in Fig. 7. After the spring is mounted on the tube 32 secured to the operating member 11 as described above, the roller 31 is moved inwardly to impart tension to the spring 25, and is moved into the relative position shown in Fig. 4. A locking pin 35 is then inserted through openings 36 formed in the walls 12 and 13 for preventing movement of the spring 25 so as to relieve itself of tension. When the spring 25 is secured with respect to the operating member 11 by the rod 35, the operating member 11 is then secured to the lid 4 by the fastening strap 24 as described above. The lid and operating member may then be mounted as a unit on the journal box by inserting the pivot pin 8 through the aligned openings provided by the hinges 6, the openings 16 in the side walls of the housing member 11, and the conventional pivot pin opening in the pivot lug 9 provided on the journal box. When the lid is thus mounted in position the parts will occupy the relative positions shown in Fig. 4. In this position it will be noted that the outer surface of the roller 31 will be in engagement with the surface 39 on the pivot lug 9. To release the pin 35, it is merely necessary to rotate the lid 4 in a clock-wise direction and thereby move the roller 31 upwardly on the surface 39. This action will impart a further tension to the spring 25 and disengage the arms 28a and 29a from the locking pin 35 which may then be readily withdrawn through the openings 36. After the locking pin 35 has been withdrawn the full tension of the spring 25 will be effective for yieldingly maintaining the lid 4 in closed position on the flanges 2 of the journal box. Attention is particularly invited to the fact that the spring 25 is the only element between the operating member 11 and the journal box. No other relatively movable parts are required in order to transmit the bias of the spring 25 to the lid 4. The bight 30 of the spring has a bearing engagement with the pivot lug 9 through the roller 31. The free ends 28 and 29 of the spring 25 have a bearing engagement with the operating member 11 at 33. The reactive force between these points of bearing engagement is transmitted directly to the operating member 11 and is applied thereby to the lid 4 at the central point 20. The lid 4 is thus yieldingly maintained in engagement with the flange 2 of the journal box.

When it is desired to move the lid 4 to an open position, a hook may be inserted through the opening 40 at the bottom edge of the lid 4 for

the purpose of pulling the lid outwardly and upwardly. This will cause the lid 4 to rotate about the pivot pin 8 to an open position. As the lid 4 is moved to an open position the roller 31 will ride upwardly on the surface 39 on the pivot lug 9, and the spring 25 will be compressed a slight additional amount. The pivot lug 9 is provided with a surface 41 angularly inclined with respect to the surface 39, and connected therewith by the rounded surface 42. If the roller 31 is moved over the rounded surface 42 into engagement with the surface 41, the cover 4 will be held in an open position until such time as the lid 4 is operated to move the roller 31 back into engagement with the surface 39.

From the foregoing it will be apparent that the spring 25 and its arrangement with respect to the operating member 11 and the pivot lug 9 provides a simplified form of mechanism for yieldingly maintaining the journal box lid in a closed position. By the use of the spring 25, the provision of additional elements such as levers and consequent lever fulcrums heretofore required are no longer necessary. There are thus no parts which are apt to become disengaged and thus get out of order. Attention is also invited to the fact that the manner in which the closing force is applied through the abutting surfaces on the lid part 19 and the lip 18 provides a desirable arrangement by which universal movement of the lid 4 is permitted relative to the operating member 11. This universal movement takes place about the single point of contact at 20. The single point of contact at 20 eliminates the complicated constructions heretofore required to provide for such universal movement.

When the lid structure shown in Figs. 1 and 4 is opened by inserting a hook through the opening 40 and pulling upwardly, the lid 4 rotates relatively to the hood 11 about the axis of the curved lip 18. This rotational movement is limited by engagement of the hinge 6 with the pivot pin 8. As soon as the hinge 6 engages with the pivot pin 8, further rotational movement of the lid 4 with respect to the hood 11 is prevented. Prior to mounting of the hood 11 and lid 4 on a journal box as during shipment to the point of assembly on a journal box, considerable rotation of these parts relative to each other may take place unless a pin 8 is inserted in the position shown in Fig. 1 to prevent such rotation. In the showings of Figs. 8 through 14, there is shown modified structure which has as one of its objects, among others, the elimination of the hinge 6 and the provision of additional structure for preventing rotational movement of the lid 4 relative to the hood 11 regardless of whether such elements are mounted on a journal box.

Referring now to Figs. 8 through 11, there is shown a modified structure for mounting the lid 4 on a journal box, the hood being designated as a whole by the numeral 11a. In this showing, it will be noted that the hinges 6, shown in Figs. 1 and 2, on the lid 4 have been omitted. The lid 4 is provided with indentations as at 45 for reinforcing purposes, and a central ridge 46 extending vertically of the lid for a purpose to be described. The strap 22 is a modified structure compared to the strap shown in Fig. 1, and has its terminal ends 47 welded to the lid 4 as at 48. The lip 18 is flattened as at 49, and the strap 22 and lid 4 have contours corresponding to the flattened shape of the lip 18. Although flattening at 49 tends to reduce the ease of rotational movement of the lid about the axis of the lip 18, the parts

are made with sufficient play to allow this motion to take place without interference from the flat 49. The departure from a substantially semi-cylindrical contour as shown in Fig. 5 by flattening as at 49 is for the purpose of enabling the lid to rotate about its center or axis 50 perpendicular to the plane of the drawing of Fig. 8. The formation of the ridge 46 provides two points 51 which engage with the under surface of the lip 18 as shown in Fig. 10, and which allow rotation of the lid 4 about the axis 50. In order that this rotation may take place, the sides 52 of the strap are formed with a curvature so that they will not bind against the walls 17 of the hood or the projection 53 of the lid. To limit rotation of the lid 4 about the axis 50 with respect to the hood 11a, the upper edge of the lid is recessed as at 54, and the lower edges 55 of the hood ears 15 project into the recess 54. In this manner, the side edges 56 of the recess 54 will engage with the sides 12 and 13 of the hood 11 to limit rotation of the lid 4 about the axis 50.

Although the lid 4 has a two-point contact with the under side of the lip 18 as at 51 in Fig. 10, it will be noted that the portion of the lid laterally outwardly of the points 51 has a taper similar to that forming the point 20 in Fig. 2. This taper which provides space 58 between the lip 18 and lid 4 will allow a self-adjusting rotation of the lid 4 with respect to the hood 11a about an axis extending in the plane of the drawing vertically of the lid as viewed in Fig. 8. The strap 22 has a taper laterally outwardly in opposite directions from its center to provide space 59 to allow this rotational movement to take place without any interference from the strap 22 since the strap 22 will rotate with the lid 4.

Although, as shown in Fig. 10, the strap 22 is shown engaged with the lip 18 at the center point 60 and the under side of the strap is shown engaged with the lid at the two points 51, and a tight engagement of the lip 18 at these three points would be effective to prevent rotation of the lid 4 about an axis perpendicular to the plane of the drawing as shown in Fig. 10, it will be understood that sufficient play is provided in the fabrication of the structure to allow this self-adjusting rotation to take place. Self-adjusting rotation of this character will have the effect of rotating one or the other of the points 51 slightly out of engagement with the under surface of the lip 18. A single point engagement of the lid with the under side of the lip 18 as at 20 in Fig. 2 of the drawings is more effective in providing this self-rotational adjustment, but the provision of the two-point engagement as at 51 facilitates a rotational adjustment of the position of the lid with respect to its axis 50 as indicated in Fig. 8.

The ridge 46 provides a vertically extending opening on the upper surface of the lid as viewed in Fig. 8 through which dirt collecting underneath the hood 11a may move downwardly and out of the space underneath the hood 11a. The provision of the vertically extending slot or opening 46 thus tends to prevent a collection of dirt underneath the hood 11a which might otherwise be effective to interfere with its operation.

As pointed out above, one of the objects of the modified lid structure shown in Fig. 8 is the elimination of the hinge eyes 6 which limit rotational movement of the lid 4 with respect to the hood 11 about a horizontal axis in opening movement thereof. To limit rotational movement of the lid 4 about a horizontal axis during opening movement thereof, the upper side 52 of

the strap 22 is provided with a ledge 62 projecting outwardly from its upper edge. The end wall 17 of the hood 11a is provided with an indentation 63 for the reception of the ledge 62 and with respect to which the ledge 62 is slightly spaced when the lid 4 is in its closed position abutting against the flanges of a journal box opening. As the lid 4 is rotated to an open position, rotational movement thereof about a horizontal axis as viewed in Fig. 4 will be effective to rotate the ledge 62 into abutting engagement with the indentation 63. In this manner, rotational movement of the lid 4 with respect to the hood 11a during opening movement thereof will be limited.

With the exception of the hood 11b, the structure shown in Figs. 12 through 14 is identical to that shown in Figs. 8 through 11. Whereas the hood 11 of Fig. 1 and hood 11a of Fig. 8 are formed from steel by a stamping operation, the hood 11b of Fig. 12 is formed of cast metal and in some respects is more rugged in construction. The hood 11b is provided with cast journals 65 having openings 66 therein in which a pivot pin is receivable to mount the hood 11b on a journal box as illustrated. Another point of distinction is in the provision of a ridge 67 formed centrally and vertically along the under surface of the lip 18 and end wall 17. The ridge 67 projects into the space provided by the groove 46 and functions to reinforce the structure forming the end wall 17 and lip 18. Since the hood 11b is formed of cast metal, the indentations 34 for mounting the tube 32 in position are pressed while the material forming such indentation is hot. Where malleable metal is used in casting the hood, the heating may be dispensed with and the indentations 34 may be cold pressed.

While I have illustrated and described several specific embodiments of my invention, it will be understood that this is by way of illustration only and that various changes and modifications may be made within the contemplation of my invention and within the scope of the following claims.

I claim:

1. In a lid structure for a journal box having a pivot lug, a lid having a horizontally extending substantially semi-cylindrical recess, a hood having a pivot at its upper end for connection to the journal box pivot lug and a substantially semi-cylindrical lip at its lower end receivable in said recess in abutting engagement with the lid, and a strap having a substantially semi-cylindrical shape for holding the lip in said recess, said strap having its ends secured to the lid, the semi-cylindrical shape of the lip, recess, and strap being effective to allow rotation of the lid relative to the hood about the axis of said lip, the lid having a groove normal to and intersecting with said recess, the portions of said lid defining said recess laterally of said groove tapering downwardly away from the hood lip received in the recess whereby the lip engages with the lid along two semi-circular lines at the edges of said groove, the tapering construction of said lid portions being effective to allow tilting action of the lid about an axis substantially normal to the axis of said recess.

2. In a lid structure for a journal box having a pivot lug, a lid having a horizontally extending substantially semi-cylindrical recess, a hood having a pivot at its upper end for connection to the journal box pivot lug and a substantially semi-cylindrical lip at its lower end receivable in said recess in abutting engagement with the lid, and a strap having a substantially semi-cylindri-

cal shape for holding the lip in said recess, said strap having its ends secured to the lid, the semi-cylindrical shape of the lip, recess, and strap being effective to allow rotation of the lid relative to the hood about the axis of said lip, the lid having a groove normal to and intersecting with said recess, the portions of said lid defining said recess laterally of said groove tapering downwardly away from the hood lip received in the recess whereby the lip engages with the lid along two semi-circular lines at the edges of said groove, the tapering construction of said lid portions being effective to allow tilting action of the lid about an axis substantially normal to the axis of said recess, said hood and lip having a ridge along the underside thereof receivable in said groove.

3. In a lid structure for a journal box having a pivot lug, a lid having a horizontally extending substantially semi-cylindrical recess, a hood having a pivot at its upper end for connection to the journal box pivot lug and a substantially semi-cylindrical lip at its lower end receivable in said recess in abutting engagement with the lid, and a strap having a substantially semi-cylindrical shape for holding the lip in said recess, said strap having its ends secured to the lid, the semi-cylindrical shape of the lip, recess, and strap being effective to allow rotation of the lid relative to the hood about the axis of said lip, the lid having a groove normal to and intersecting with said recess, the portions of said lid defining said recess laterally of said groove tapering downwardly away from the hood lip received in the recess whereby the lip engages with the lid along two semi-circular lines at the edges of said groove, the upwardly projecting sides of the semi-circular strap having its ends curved away from the sides of said semi-circular recess so that the lid may pivot relatively to the hood about an axis centrally of and normal to said lid.

4. In a lid structure for a journal box having a pivot lug, a lid having a horizontally extending substantially semi-cylindrical recess, a hood having a pivot at its upper end for connection to the journal box pivot lug and a substantially semi-cylindrical lip at its lower end receivable in said recess in abutting engagement with the lid, and a strap having a substantially semi-cylindrical shape for holding the lip in said recess, said strap having its ends secured to the lid, the semi-cylindrical shape of the lip, recess, and strap being effective to allow rotation of the lid relative to the hood about the axis of said lip, the lid having a groove normal to and intersecting with said recess, the portions of said lid defining said recess laterally of said groove tapering downwardly away from the hood lip received in the recess whereby the lip engages with the lid along two semi-circular lines at the edges of said groove, the upwardly projecting sides of the semi-cylindrical strap having its ends curved away from the sides of said semi-cylindrical recess so that the lid may pivot relatively to the hood about an axis centrally of and normal to said hood, the lip, lid, and strap each having flattened portions extending longitudinally along the bottom of their semi-cylindrical shape to facilitate rotational adjustment about said last-named axis.

5. In a lid structure for a journal box having a pivot lug, a lid having an elongated substantially semi-cylindrical recess in and extending transversely and centrally of its outer surface, the axial length of said recess being a substantial portion of the width of the lid, a hood having a pivot at its upper end for connection to

the journal box pivot lug and a substantially semi-cylindrical lip at its lower end, said lip being positioned in said recess in abutting engagement with said lid and having an axial length slightly less than the axial length of said recess, and a strap holding said lip in said recess with its central portion being of semi-cylindrical shape and having a nesting engagement with said lip, said lid recess, hood lip, and central strap portion having a substantially common axis parallel to the axis of said pivot whereby the lid and strap may have limited rotation relative to the hood about said lip axis, said strap having its ends extending axially beyond the ends of said lid recess and provided with rigid connections to the lid.

6. A lid structure as claimed in claim 5 characterized by said lip, strap, and lid recess having their engaging surfaces tapering in an axial direction relative to each other to allow said lid and strap a limited rocking movement relative to said hood about a vertical axis in the plane of the lid and extending centrally of and normal to said common axis.

7. A lid structure as claimed in claim 5 characterized by said central strap portion and lid recess each having a pair of end surfaces which respectively face opposite surfaces of said lip and diverge angularly outwardly in an axial direction relative to the lip surface faced thereby whereby said lid and strap may have limited rocking movement relative to said hood about a vertical axis extending centrally of and normal to said common axis.

8. In a lid structure for a journal box having a pivot lug, a lid having an elongated substantially semi-cylindrical recess in and extending transversely and centrally of its outer surface, the axial length of said recess being a substantial portion of the width of the lid, a hood having a pivot at its upper end for connection to the journal box pivot lug and a substantially semi-cylindrical lip at its lower end, said lip being positioned in said recess in abutting engagement with said lid and having an axial length slightly less than the axial length of said recess, and a strap holding said lip in said recess and having an axial length greater than the length of said recess with its central portion being of semi-cylindrical shape and having a nesting engagement with said lip, said lid recess, hood lip, and central strap portion having a substantially common axis parallel to the axis of said pivot whereby the lid and strap may have limited rotation relative to the hood about said lip axis, said strap having its ends extending axially beyond the ends of said lid recess and provided with rigid connections to the lid, said strap, lid recess, and lip including means on their engaging surfaces providing for limited rotation of the lid and strap relative to the hood about an axis normal to the lid.

9. In a lid structure for a journal box having a pivot lug, a lid having an elongated substantially semi-cylindrical recess in and extending transversely and centrally of its outer surface, the axial length of said recess being a substan-

5 tial portion of the width of the lid, a hood having a pivot at its upper end for connection to the journal box pivot lug and a substantially semi-cylindrical lip at its lower end, said lip being positioned in said recess in abutting engagement with said lid and having an axial length slightly less than the axial length of said recess, and a strap holding said lip in said recess and having an axial length greater than the length of said

10 recess with its central portion being of semi-cylindrical shape and having a nesting engagement with said lip, said lid recess, hood lip, and central strap portion having a substantially common axis parallel to the axis of said pivot whereby

15 the lid and strap may have limited rotation relative to the hood about said lip axis, said strap having its ends extending axially beyond the ends of said lid recess and provided with rigid connections to the lid, said strap, lid recess, and lip

20 including means on their engaging surfaces providing for limited rotation of the lid and strap relative to the hood about an axis in the plane of the lid and normal to said common axis.

10. In a lid structure for a journal box having
25 a pivot lug, a lid having an elongated substantially semi-cylindrical recess in and extending transversely and centrally of its outer surface, the axial length of said recess being a substantial portion of the width of the lid, a hood having
30 a pivot at its upper end for connection to the journal box pivot lug and a substantially semi-cylindrical lip at its lower end, said lip being positioned in said recess in abutting engagement with said lid and having an axial length slightly
35 less than the axial length of said recess, and a strap holding said lip in said recess and having an axial length greater than the length of said recess with its central portion being of semi-cylindrical shape and having a nesting engagement
40 with said lip, said lid recess, hood lip, and central strap portion having a substantially common axis parallel to the axis of said pivot whereby the lid and strap may have limited rotation relative to the hood about said lip axis, said strap
45 having its ends extending axially beyond the ends of said lid recess and provided with rigid connections to the lid, said strap, lid recess, and lip including means on their engaging surfaces providing for limited rotation of the lid and strap
50 relative to the hood about two other axes extending normal to each other and to said concentric axes, one of said other axes being in the plane of the lid and the other being normal to the plane of the lid.

HOWARD J. STEWART.
